(57) **CLAIM**

The ornamental design for color coded barbecue grill and smoker thermometer gauge, as shown and described.

DESCRIPTION

FIG. 1 is a top angled elevational view of the temperature gauge showing my new design;

FIG. 2 is a face front plan view thereof;

FIG. 3 is a back side plan view thereof;

FIG. 4 is a right side elevational view thereof;

FIG. 5 is a left side elevational view thereof; and,

FIG. 6 is a front side elevational view thereof which is also mirrored for the back side elevational view.

My BBQ Grill / Smoker color coded thermometer gauge is characterized by its front segmented and colored dial display with large pointer showing 3 printed ideal cooking temperature ranges, smoke, bbq, grill and corresponding actual temperature reading on the outside edge of the dial. My ornamental design is also unique in its side views as show in the drawings in its multistep raised dial mounting on a grill or smoker which is unlike flat mounted versions currently on the market.
